(57) **CLAIM**

The ornamental design for a horticulture lighting controller chassis, as shown and described.

DESCRIPTION

FIG. 1 is a perspective view of a horticulture lighting controller chassis, as viewed from the front, showing our new design;

FIG. 2 is a perspective view of the horticulture lighting controller chassis shown in FIG. 1, as viewed from the rear; FIG. 3 is a right side view of the horticulture lighting controller chassis shown in FIG. 1;

FIG. 4 is a left side view of the horticulture lighting controller chassis shown in FIG. 1;

FIG. 5 is a top elevation view of the horticulture lighting controller chassis shown in FIG. 1;

FIG. 6 is a bottom elevation view of the horticulture lighting controller chassis shown in FIG. 1;

FIG. 7 is a front plan view of the horticulture lighting controller chassis shown in FIG. 1; and,

FIG. 8 is a rear plan view of the horticulture lighting controller chassis shown in FIG. 1.

The broken-line disclosure shown in the views is understood to represent portions of the article in which the claimed design is embodied, but which form no part of the claimed design.
